United States Patent Office

Des. 229,500

Patented Dec. 4, 1973

229,500

BATTERY CHARGER OR SIMILAR ARTICLE

Donald K. Krumin and Richard J. Toth, Fort Lauderdale,
Fla., assignors to Motorola, Inc., Franklin Park, Ill.

Filed Oct. 13, 1971, Ser. No. 188,632

Term of patent 14 years

Int. Cl. D13—02

U.S. Cl. D26—15 B

FIG. 3

FIG. 4

FIG. 1 is a front perspective view of a battery charger or similar article showing our new design;

FIG. 2 is a rear elevation thereof;

FIG. 3 is a top plan view thereof;

FIG. 4 is a bottom plan view thereof.

The side opposite FIG. 1 is a mirror image of the side shown.

We claim:

The ornamental design for a battery charger or similar article, substantially as shown and described.
